Attorney.

UNITED STATES PATENT OFFICE

CHARLES NOE AND HENRY KREISS, OF ELIZABETH, NEW JERSEY

VALVE FOR CELLAR DRAINS

Application filed September 24, 1928. Serial No. 307,814.

This invention relates to cellar or basement floor drains, and particularly to means for preventing the flooding of the cellar by back-flow from the sewer.

- 5 It is an object of the invention to provide an inexpensive, simple, compact, readily applied appliance for this purpose, and one that is not liable to get out of order, and that is easily manipulable.
- 10 The invention includes means for avoiding the cost of mounting a drain-closing valve upon a supporting framework secured to the floor or wall of the cellar. In place of such a framework, there is used a post, 15 constituting a valve support or anchorage. The post is inserted within the neck of the floor drain and fits tightly therein, and projects above the cellar floor, or at least rises out of the neck of the drain. This post anchorage prevents the valve from being laterally displaced. It is hollow or of tubular form, permitting the cellar to drain therethrough, and it has side inlets or perforations for such purpose. The valve structure 20 telescopes over said post, and its annular washer or packing element (which likewise surrounds said post) can be forced down within the cup which is usually formed upon the upper end of the cellar drain. The hollow post 25 may be open at the top, and said valve may have a tubular body extending above said post. Within this tubular body or standpipe the back-water from the sewer can rise harmlessly. Said hollow valve-element can be 30 lifted freely upon said post or anchorage, to open the valve, and uncovers the side inlets in the post, permitting cellar drainage.

The remaining support of the valve-element is conveniently attached to a floor rafter which usually forms part of the cellar ceiling. This will anchor or prevent lateral displacement of the upper end of the valve-element, which extends from bottom to top of the cellar. Thus the necessity of 45 using a framework or other means to support the valve from the floor or wall is eliminated, and an inexpensive, inconspicuous, compact, out-of-the-way valve is produced.

Thus preferably there rises from the cellar floor a standpipe which opens at the bot-

tom into the cellar drain, and which at any time can be forced down to close the drain. When it is so closed, the back-flow from the sewer may rise harmlessly in the standpipe. The device occupies practically no floor room, 55 because it may be located in a corner of the cellar out of the way, and also because the means for effecting the opening and closing of the valve is mounted at the top of the standpipe, and has a bearing or support in or 60 upon the first-floor structure. Preferably a threaded plate is fastened upon the under side of the floor beams, and a shank is threaded up through said plate and provided with a cross-handle or other rotating 65 means; said shank having a swivel connection to the standpipe, whereby rotation of the shank will raise and lower the valve without necessarily rotating the same.

For guiding the standpipe or vertical tube 70 up and down upon the post, which is fixed tightly into the cellar drain, the bottom of the standpipe may be provided with an interior circular flange. To the bottom of the standpipe is secured a washer or gasket, 75 which may be of rubber or other yielding material.

The perforations in the post, through which the cellar drains, may serve as a screen to prevent large objects from falling 80 into the drain.

Other features and advantages will hereinafter appear.

In the accompanying drawings,

Figure 1 is a part-sectional elevation of one 85 form of the present invention, showing the valve closed and back-flow of water from the sewer prevented.

Figure 2 is a vertical sectional view of the lower portion of the closed valve, etc. 90

Figure 3 is a view similar to Figure 2 but showing the valve open and the cellar draining through the post.

In the floor 9 of the cellar is provided the usual vertical drain pipe 10, for which the 95 invention is readily adapted, no alterations being required therein. Fixed in the neck of the pipe is a hollow post 11. Extending upwardly from the floor is a tubular riser 12, forming the valve, which is in closed position 100

at Figure 1, and in which harmlessly rises the back-flow 13 from the sewer.

To the bottom of said riser or standpipe is secured an annular soft rubber or other washer, packing, or gasket 14, which in Figures 1 and 2 is forced down upon the bottom or saucer portion 15 of the cellar drain, which usually surmounts the neck-portion 16 thereof.

10 The closing of the valve is effected by means of handles 17 which project from a vertical shaft 18 having at its top a threaded shank 19, which is screwed into a threaded hole 20 in a metal plate or fixture 21, which is held by screws 22 up against the bottom edges of ceiling beams 23, which support the flooring 24 of the first story of the building. In the floor may be bored a hole 25 for convenience, giving clearance for the screw, and also 15 permitting inspection, so that it can be ascertained whether the valve is closed or open by merely noting the position of the threaded shank 19 in the hole 25.

Instead of fixing the handle 17 directly 20 upon the valve 12, there is preferably provided a swivel or loose connection, to permit the screw 19 to be revolved without turning the valve, thereby avoiding unnecessary pressure upon and damage to the washer 14, so that it 25 is not caused to grind upon the cellar drain cup portion 15. This loose connection may be of any suitable type, and there is shown, for example, a stem 26 rising from a neck 27 which is provided upon the top of the stand- 30 pipe 12, said stem 26 being secured in said neck by means of screws 28. The top of this stem is held by a set-screw 29 within a collar 30 having a flange or brim 31 under which catches an internal flange or brim 32 formed 35 in the bottom of a nut 33, which is threaded upon a boss 34 and fixed thereto by a set-screw 35. Said boss is secured upon the lower end of shaft 18 by means of a set-screw 36. Thus it 40 will be seen that the shaft 18 may be revolved without revolving the washer 14, since the nut 33 may slip around freely under the stationary flange 31.

Said annular packing, gasket or washer 14 may be attached to the bottom of the valve in 45 various ways, as, for example, by forming a reflex interior flange 37 on the bottom of the valve or standpipe 12, said flange being so shaped as to provide on its under side an annular recess 38 within which the washer 50 14 is tightly and permanently gripped.

Said flange 37 may include an innermost annular wall 39 which may slide up and down 55 loosely on the tubular post 11, rising from the neck 16 of the cellar drain. The lower portion 41 of said post 11 is tightly forced within said drain neck, so as to be rigidly supported thereby.

Usually the valve stands in the open Figure 3 position; but upon the occurrence of a 60 storm, or for other reason, the handle 17 may

be rotated to screw the shaft 18 downwardly in the fixture 21, thereby carrying down the valve 12 and the washer 14 on the bottom thereof, and pressing the latter firmly down on the bottom of cup 15 in drain pipe 10, and sealing the latter. If water backs up from the sewer, it collects at 13 in the standpipe without doing any damage or causing undue pressure at any point. After the water in the sewer has receded, the arms 17 may be revolved reversely to lift the closure 14 and open the cellar drain, as at Figure 3.

In the tubular post or guide 11 are formed inlet holes 42, and this post may serve as a screen and prevent large objects from being 70 floated into the cellar drain 10. These openings 42 are idle when the valve is closed, as at Figure 1.

Variations may be resorted to within the scope of the invention, and portions of the 75 improvements may be used without others.

Having thus described our invention, we claim:

1. A valve-device for closing a floor drain, 80 including a hollow post rising from the drain, openings being provided in said post for draining the floor through said post when the valve is open, a valve capable of being raised and lowered upon said post, a washer upon said valve to seal said openings, an operating member having a handle and connected to the valve, and means supportable by the ceiling and co-operative with said operating member to raise and lower the valve. 95

2. A valve-device for closing a floor drain, 100 including a hollow post provided with a floor-draining perforation and having its lower portion fixed tightly within the drain and its upper portion projecting, a valve fitted upon the projecting portion of said post and having a drain-sealing washer, a threaded device connected to said valve, and a support co-operative with said threaded device to raise and lower said valve. 105

3. A valve-device for closing a floor drain, 110 including a hollow post provided with a floor-draining perforation and having its lower portion fixed tightly within the drain and its upper portion projecting, a valve fitted upon the projecting portion of said post and having a drain-sealing washer, a threaded device connected to said valve, and a support co-operative with said threaded device to raise and lower said valve, said threaded device extending up to the ceiling, and said support including a threaded member 115 for attachment to the ceiling. 120

4. A valve-device for closing a floor drain, 125 including a post having a lower portion for insertion in the drain to be rigidly supported thereby, said lower portion hollow to permit draining, and said post having a cellar-draining perforation, a valve including a member slidably engaging said post for up and down motion and having a drain-seal- 130

ing washer, means for operating said valve, and a support for said operating means.

5. A valve-device for closing a floor drain, including a hollow post for insertion into a drain to be supported thereby, said post provided with cellar-draining means effective when the valve is open, a valve having a washer surrounding said post to seal the drain, and means for raising and lowering said valve.

10. 6. A valve-device for closing a floor drain, including a hollow post for insertion into a drain to be supported thereby, said post provided with cellar-draining means effective when the valve is open, a valve having a washer surrounding said post to seal the drain, and means for raising and lowering said valve, said raising and lowering means including a rotary threaded member rising to the ceiling and provided with a handle and a co-operative threaded member for affixing to the ceiling.

15. 7. A valve-device for closing a floor drain, including a hollow post for insertion into a drain to be supported thereby, said post provided with cellar-draining means effective when the valve is open, a valve having a washer surrounding said post to seal the drain, and means for raising and lowering said valve, said raising and lowering means including a rotary threaded member rising to the ceiling and provided with a handle and a co-operative threaded member for affixing to the ceiling, said valve including a hollow body telescoping over said post and having said washer fixed to the bottom thereof, said rotary threaded member connected to said hollow body.

20. 8. A valve-device for closing a floor drain, including a hollow post for insertion into a drain to be supported thereby, said post provided with cellar-draining means effective when the valve is open, a valve having a washer surrounding said post to seal the drain, and means for raising and lowering said valve, said raising and lowering means including a rotary threaded member rising to the ceiling and provided with a handle and a co-operative threaded member for affixing to the ceiling, said valve including a hollow body telescoping over said post and having said washer fixed to the bottom thereof, said rotary threaded member being swiveled to said valve-member.

25. 9. A closure for a cellar drain including a hollow post fixed within the neck of a drain cup and projecting thereabove, said post having an inlet for draining the cellar, a tubular valve telescoping over said post and provided upon its bottom with a packing element surrounding said post, and means to lower said valve to cause said packing to seal the drain cup.

30. 10. A closure for a cellar drain including a hollow post fixed within the neck of a drain

cup and projecting thereabove, said post having an inlet for draining the cellar, a tubular valve telescoping over said post and provided upon its bottom with a packing element surrounding said post, and means to lower said valve to cause said packing to seal the drain cup, said hollow post open at the top, and said valve having a tubular body extending above the post to collect back-water from the sewer.

35. 11. A closure for a cellar drain including a hollow post fixed within the neck of a drain cup and projecting thereabove, said post having an inlet for draining the cellar, a tubular valve telescoping over said post and provided upon its bottom with a packing element surrounding said post, and means to lower said valve to cause said packing to seal the drain cup, said valve being liftable freely upon said post and uncovering said inlet when the valve is open.

40. 12. A closure for a cellar drain including a hollow post fixed within the neck of a drain cup and projecting thereabove, said post having an inlet for draining the cellar, a tubular valve telescoping over said post and provided upon its bottom with a packing element surrounding said post, and means to lower said valve to cause said packing to seal the drain cup, said means including a support to be secured to the ceiling.

45. 13. The combination with a cellar drain, of a standpipe extending up from said drain, a washer upon the bottom of the standpipe to seal the drain, and means for raising and lowering said standpipe, said raising and lowering means having an attachment to the ceiling.

50. 14. The combination with a cellar drain, of a standpipe extending up from said drain, a washer upon the bottom of the standpipe to seal the drain, means for raising and lowering said standpipe, said raising and lowering means having an attachment to the ceiling and including a threaded plate fastened upon the under side of floor beams, a shaft having a part threaded into said plate, a handle for said shaft, and a suitable connection between said shaft and said standpipe.

55. 15. The combination with a cellar drain, of a standpipe extending up from said drain, a washer upon the bottom of the standpipe to seal the drain, means for raising and lowering said standpipe, said raising and lowering means having an attachment to the ceiling and including a threaded plate fastened upon the under side of floor beams, a shaft having a part threaded into said plate, a handle for said shaft, and a suitable connection between said shaft and said standpipe, a hollow post being provided in said cellar drain and projecting up therefrom, and said standpipe telescoping over said post.

60. 16. The combination with a cellar drain, of a standpipe extending up from said drain,

a washer upon the bottom of the standpipe to seal the drain, means for raising and lowering said standpipe, said raising and lowering means having an attachment to the ceiling and including a threaded plate fastened upon the under side of floor beams, a shaft having a part threaded into said plate, a handle for said shaft, and a suitable connection between said shaft and said standpipe, a hollow post being provided in said cellar drain and projecting up therefrom, and said standpipe telescoping over said post, said standpipe having an interior circular flange, and said washer confined by said flange, and said flange engaging said post.

17. The combination with a cellar drain, of a standpipe extending up from said drain, a washer upon the bottom of the standpipe to seal the drain, means for raising and lowering said standpipe, said raising and lowering means having an attachment to the ceiling and including a threaded plate fastened upon the under side of floor beams, a shaft having a part threaded into said plate, a handle for said shaft, and a suitable connection between said shaft and said standpipe, a hollow post being provided in said cellar drain and projecting up therefrom, and said standpipe telescoping over said post, said standpipe having an interior circular flange, and said washer confined by said flange, and said flange engaging said post, said hollow post having a series of cellar-draining openings which are closed by said valve when the drain is sealed.
